Primary Examiner — Paula Allen Greene(74) *Attorney, Agent, or Firm* — Winstead PC(57) **CLAIM**

I claim the ornamental design for a collar device, as shown and described.

DESCRIPTION

FIG. 1 shows a perspective view of a collar device; FIG. 2 shows a perspective view of a collar device; FIG. 3 shows a left side view of a collar device; FIG. 4 shows a right view of a collar device; FIG. 5 shows a front view of a collar device; FIG. 6 shows a back view of a collar device; FIG. 7 shows a top view of a collar device; and, FIG. 8 shows a bottom view of a collar device.

The broken lines depict environment that forms no part of the claimed design. The dotted lines on the surface portions indicate contour and not surface decoration.

1 Claim, 3 Drawing Sheets---
